UNITED STATES PATENT OFFICE.

JOSÉ PALACIOS, OF NEW YORK, N. Y.

SLIDING LOCK.

Application filed March 27, 1924, Serial No. 702,302. Renewed August 25, 1926.

This invention relates generally to locks, having more particular reference to a lock in which a bolt is secured in locking position by a number of padlocks, the invention having for an object the provision of a novel and improved lock of this type.

For further comprehension of the invention, and of the objects and advantages thereof, reference will be had to the following description and accompanying drawing, and to the appended claims in which the various novel features of the invention are more particularly set forth.

Fig. 1 of the drawing is a side view showing my improved lock applied to a door.

Fig. 2 is a face view.

Fig. 3 is a horizontal sectional view thereof, taken on the line 3—3 of Fig. 2.

Fig. 4 is a vertical sectional view taken on the line 4—4 of Fig. 1.

Referring now to the drawing, the reference numeral 10 indicates a hollow guide member or casing through which a bolt 11 extends freely, this member having side flanges 10' formed with suitable apertures to receive fastening screws 12 whereby the member is secured on a door to which my improved lock is applied, a portion of the door being indicated at D. A like casing element 10^a is secured as by screws 12^a to the door frame F. This bolt is bifurcated at the rear end thereof to form a pair of hinge eyes 14 between which engaged a hinge element 15 on the rear end of an elongated rectangular frame member 16 which fits snugly around the casing member 10 and is of greater length than the latter, a hinge pintle 17 being fixed in the hinge eyes 14 and passing freely through the hinge element 15 on the frame 16.

Projecting from opposite ends of the frame member 16 are integral ears 19 which have apertures 20 therein to receive the shackles of padlocks, while similar ears 21 and 21^a having apertures 22 therein, are formed on the removed ends of the casing elements 10 and 10^a the ears on the frame member registering with those on the casing member. The forward end of the bolt extends beyond the front end of the frame member 16 and the bolt is here shown as formed with a notch 24 on its outer face into which the edge of the end element of the frame member extends. The bolt is adapted to be projected into the casing 10 to lock the door. To limit rearward move-

ment of the bolt the casing 10^a is formed with an extension in the form of a flat strap 27 which has an outturned end 28 against which the rear end of the bolt abuts when the bolt is retracted. The frame 16 may be provided with a knob or handle 29 fixed on a crosspiece 29' on the frame.

I preferably provide in addition a secret locking member which prevents withdrawal of the bolt even when the padlocks are taken from the ears 19, 21 and the frame 16 swung outward. The lock comprises a lever 30 pivoted at one end as at 32 in a longitudinal slot 33 in the bolt 11 and having near its other end an outturned catch 34 which engages in a suitable socket in the casing element 10^a the lever being normally held in locking position by a spring 35 fixed at one end to the bolt and bearing on the lever. The free end of this lever is beveled as at 36 to form a cam element which is adapted to be engaged by a lip 37 on the hinge member 15 of the frame 16, this member 15 having a slot 38 therein through which the hinge pin 17 passes. To release the catch 34 from the casing member 10, the frame 16 must be swung outward a certain distance and then moved forward until the lip 37 engages the end of the lever 30 and depresses the latter. The bolt 11 is then freed and may then be retracted.

To effect the initial retracting movement of the bolt the ears 14 are grasped and the bolt pulled rearwardly, while the frame 16 is held in position with the member 37 engaged with the end of the lever 30, the frame and the bolt being moved backwardly as a unit. When the bolt has been retracted sufficiently to bring the catch 34 out of registry with the socket in the casing element 10 further retraction of the bolt may be effected by pulling on the frame 16.

Having thus described my invention what I claim as new and desire to protect by Letters Patent of the United States is as follows:

1. A lock comprising a casing element, a bolt slidable therein, a frame hinged to the rear end of said bolt and adapted to surround the casing element, and registering ears on said frame and said casing adapted to receive the shackles of padlocks.

2. A lock comprising a casing element adapted for mounting on a door, a bolt slidable therein, a keeper element adapted for mounting on a door frame, a frame hinged

to the rear end of said bolt and adapted to surround the casing and keeper element, and registering ears on said frame and said casing adapted to receive the shackles of padding locks, the bolt having a notch therein near its forward end in which the end element of the said frame engages.

3. A lock comprising a casing element adapted for mounting on a door, a bolt slideable therein, a keeper element adapted for mounting on a door frame, a frame hinged to the rear end of said bolt and adapted to surround the casing and keeper element, and registering ears on said frame and said casing adapted to receive the shackles of padding locks, and a tail-piece projecting rearwardly from said casing and forming an abutment to limit rearward movement of said bolt.

4. A lock comprising a casing element adapted for mounting on a door, a bolt slideable therein, a keeper element adapted for mounting on a door frame, a frame hinged to the rear end of said bolt and adapted to surround the casing and keeper element, and registering ears on said frame and said casing adapted to receive the shackles of padding locks, and a concealed locking element holding said bolt against movement in said casing, said locking element being adapted for release by manipulation of said frame.

5. A lock comprising a casing element

adapted for mounting on a door, a bolt slideable therein, a keeper element adapted for mounting on a door frame, a frame hinged to the rear end of said bolt and adapted to surround the casing and keeper element, and registering ears on said frame and said casing adapted to receive the shackles of padding locks, and a concealed locking element holding said bolt against movement in said casing, said locking element being adapted for release by manipulation of said frame, and comprising a lever having a catch thereon adapted to engage the bolt.

6. A lock comprising a casing element adapted for mounting on a door, a bolt slideable therein, a keeper element adapted for mounting on a door frame, a frame hinged to the rear end of said bolt and adapted to surround the casing and keeper element, and registering ears on said frame and said casing adapted to receive the shackles of padding locks, a lever fulcrumed at one end in a slot in said bolt, a catch on the lever adapted to engage the said casing, a slotted hinge ear on said frame, and a lip on said hinge ear adapted to engage the said lever to release the said catch.

In testimony whereof I have affixed my signature.

JOSÉ PALACIOS.
